OPTICAL AIMING-DEVICE FOR MACHINE GUNS

Karl Jung, Munich, Germany

Application December 16, 1931, Serial No. 581,359,
and in Hungary December 19, 1930

5 Claims. (Cl. 88—2.2)

The optical aiming-device for machine-guns described in the following affords the gunner a far larger range of sight of the country than heretofore, his position being more comfortable 5 at the same time. Thus the sighting of objects, specially of objects moving rapidly, as for instance aeroplanes, is made considerably easier, as the search for the object is effected by means of the aiming-device itself and not by means of a 10 field-glass and the like as heretofore.

Fig. 1 of the drawings is a front elevational view of the device, Fig. 2 an axial cross-section of the aiming-device, Fig. 3 is a top plan view of the device (without light-protection). Fig. 4 is a section at line *a* in Fig. 2. Fig. 5, shows a safety-device for the telescope lens. Figures 6 to 9 illustrate a modified form of the present invention in which means for laterally adjusting the deviation plate are provided. Figure 6 is a front elevational view, Figure 7 shows a part of the device in axial cross section, Figure 8 is a section at line *a* of Figure 7, and Figure 9 is a top plan view of the device, the light protection being omitted. Figures 10 and 11 show further modifications of 25 the present invention. Figure 10 shows a meniscus-shaped deviation plate provided with a central compensation lens, and Figure 11 shows a second style of construction of the arrangement illustrated in Figure 10.

30 A lens *O* of great intensity of light, projecting a perspective plane of about 40 degrees, delineates a sharp, upright picture of the country over the mirror *B* on a glass plate *P* lying in its focus plane. For the purpose of exact focussing the lens *O* is so arranged, as to be movable axially and fixable. 35 The whole arrangement is encased in a steel casting *G*, the upper border of which (in the focus plane of the lens) is constructed as a flange *F*. In this flange *F* there lies immovable the glass-plate *P* which is extremely finely, almost transparently matted with the exception of a central, 40 circular field *C* of varied size (not lined in Fig. 4).

Above the glass plate *P* the (of course completely transparent) deviation-plate *A* with the hair-cross or mark-pin *Z* and the scale *S* is arranged. The deviation plate *A* which lies in the ring *R* flattened on two sides, is movable and fixable in its plane in the direction of the arrow *x*—*x* (Fig. 3) for purposes of elevation (*x*—axis). 45 Any known type of a tooth-drive, screw or worm drive may be used for moving and locking the deviation plate to produce elevation thereof (see Figures 6 and 7). As guides serve the two segment-shaped ledges *N* supplied with grooves and resting on flange *F*. The degree of the displace- 50

ment effected can be read at any time at a single glance with the aid of the scale *S* resting on the deviation plate *A* and the mark *M* on the matted plate *P*, without necessity of interrupting the observation through the aiming-device.

60 If for lateral correction also a lateral displacement (*y*—axis) of the deviation-plate is required, same can of course be effected without difficulty by means of an intermediate ring. For this purpose the ring or frame *N'*, which corresponds to the portion *N* shown in Fig. 1, is guided in the direction *y* on the flange *F*. Movement is produced by the drive *U* the shaft of which is disposed in the ring or frame *N'* meshing by the toothed wheel *U'* with the toothed flange *F* (Fig. 70 7). In order to be able to move the deviation plate in the direction *x* the ring *R* is movably disposed in the frame *N'*. Movement of the plate may be produced manually, while the locking thereof is brought about by means of a clamping 75 screw *V*.

The ring *R* serves as a carrier for the light-protection *D* made of rubber with spiral springs arranged inside and also for the ocular *E* arranged centrally above the field *C* (not lined) 80 of plate *P*. The exact focussing of the ocular is effected by turning it round its axis, the very thin mounting being supplied with an outer thread.

85 When looking into the aiming-device there appears on the matted plate in correspondence with the respective perspective plane of the lens *O* a stretch of country of corresponding size, directly and binocularly perceptible for the eyes protected by light protection *D* against 90 lateral light, the stretch of country appearing in the aiming-field *C* becoming visible magnified through the ocular *E*. Besides, each point of the glass picture plane of *P* can be observed magnified according to requirements by means of a 95 magnifier *L*, which can be displaced in the plane in all directions by the handle *H* and fixed by the clog *K*. In this manner it is possible to grip the object quickly and to bring it into the hair-cross or on the mark-pin by moving the machine-gun.

100 The magnifier *L* renders furthermore a greater ocular enlargement possible, if placed between ocular *E* and the deviation-plate *A*. It is also advantageous for an exact adjustment and reading of the elevation by means of the scale *S* and the mark *M*.

105 For special cases the ocular *E*, resting with the support *T* with bayonet-catch in ring *R*, can be taken out without difficulty, so that the picture 110

visible on the glass plate P may be regarded solely with the magnifier L.

In order to obtain an aiming-device fit for active service, the steel-casing enclosing the lens, 5 and the mirror forms with the immovable matted glass plate a waterproof and dustproof entirety. Light-protection and deviation-plate may be pulled out from the groove-guide as a whole, which makes an easy cleaning of the matted plate 10 possible. It proves to be specially convenient and suitable—entirely eliminating the lower plate P—to mat semi-transparently the deviation-plate A with the exception of the centre-field and to bring the point of a rigid steel-pointer welded 15 with the casing into play on its scale S, the whole arrangement coming to lie in the mat field in the prolongation of the red mark-pin Z, that is "downwards" seen by the gunner.

The semi-transparent matting of A may also 20 be replaced by a weakly opalescent coat or the like.

It is likewise sufficient to give the deviation plate but a small (meniscus-like) bend which is compensated in a central field by a corresponding 25 lens fastened by putty.

The arrangement of ocular E and magnifier L may be simplified, if L represents half of a Ramsden-ocular, whose second (eye) lens fastened to the body of the telescope is put by hand into the 30 mounting of L to effect a greater enlargement. Finally it is sufficient to limit the light-protection D to a semi-circular low cramp open towards the gunner, which facilitates the cleaning of the deviation-plate, if it should become dim or dusty.

35 The searching for and sighting of the object of aim as well as the adjustment and reading of the elevation is effected during the observation by the aiming-device; consequently the gunner does not need to direct his attention towards objects outside of same. Thus a continuous and effective firing becomes possible. Further the insight from above and the clear and easily surveyable picture of the country gives the gunner (also in an aeroplane) the feeling of security and 40 the tranquility for introducing the object of aim into the blank central shooting-field with the mark-pin.

The telescope lens O would then have to protrude through a correspondingly large orifice Q 50 of the steel-screen SS at the machine-gun MG, the telescope and the gunner being exposed to the projectiles striking there. To avoid this disadvantage one may sight over a pair of parallel mirrors Sp, Sp', (Fig. 5) disposed in a bullet-proof steel-casing SK, the raising of the optical axis by a few centimetres not being of any importance. The steel-casing SK is suspended from 55 the steel-screen SS by means of a bayonet-catch and the mirrors can, if necessary, also be exchanged during the fight in the case of breaking.

What I claim is:

1. An optical aiming device for guns, comprising a projection lens, optical means for visualizing objects projected thereon by said lens, a mark pin for sighting, a casing for the aiming device, a magnifying lens rigidly attached to said casing over the visualizing means, and a second magnifying lens movably disposed in said casing and adapted to be moved over the entire area of said visualizing means, said two magnifying lenses being adapted to combine their power. 80

2. An optical aiming device for guns comprising a casing, a projection lens mounted therein, a ground glass provided with a clear portion secured to the casing, the longitudinal axis of the ground glass being disposed parallel with the optical axis of the said lens, a reflecting surface disposed between said lens and the ground glass to project the light rays condensed by said lens onto the ground glass, a transparent plate provided with a mark pin superimposed on said ground glass, said mark pin serving for sighting purposes and means for longitudinally and laterally adjusting the said transparent plate in said casing. 90

3. An optical aiming device for guns comprising a casing, a projection lens mounted therein, a substantially meniscus shaped curved transparent plate movably mounted in said casing, the optical axes of said lens and plate being perpendicular to each other, a reflecting surface mounted in said casing between said lens and plate to project the light rays condensed by said projection lens to said plate, a mark pin rigidly attached to said casing over said plate, said plate comprising a rectifying lens at the centre thereof to prevent distortion, a stationary and a movable magnifying lens mounted over said plate, the power of said magnifying lenses being combinable and said stationary lens being centered in relation to said plate. 100

4. An optical aiming device for guns, comprising a casing, a projection lens mounted therein, a ground glass provided with a clear portion secured to the casing, the longitudinal axis of the ground glass being parallel with the optical axis of said lens, a reflecting surface between said lens and the ground glass to project light rays condensed by the lens onto the ground glass, a transparent plate superimposed on the ground glass, said plate having a mark pin for sighting purposes, a stationary magnifying lens secured to the casing above the clear portion in the ground glass, and a second magnifying lens movable in said casing over the entire area of said transparent plate, the power of said two magnifying lenses being combinable. 125

5. An optical aiming device, comprising the combination of claim 4 with means for adjusting the transparent plate in relation to the ground glass. 130
